DAMPENING ROLLER REMOVAL AND
INSERTION MECHANISM

Arthur G. Jacobson, Chicago, Ill., assignor, by
mesne assignments, to Miehle Printing Press
and Manufacturing Company, Chicago, Ill., a
corporation of Delaware

Application May 20, 1947, Serial No. 749,263

7 Claims. (Cl. 101—147)

1

The invention relates to dampening mechanism for lithographic or offset printing presses where the plate or form which bears the image to be printed must be dampened before the printing ink is applied to it, the purpose of this dampening procedure being to repel the ink in the non-printing areas of the plate.

More specifically, the invention consists in the provision of improved means whereby one of the dampening rollers can be conveniently removed from its operative position and returned to said position and locked without disturbing its setting, or without disturbing the setting of the other dampening rollers, and wherein the locking function will be accomplished automatically.

Conventional dampening mechanism as is used on offset printing presses includes a water fountain in which a brass fountain roller is immersed and mounted to rotate continually, one or more molleton covered dampening rollers which are brought into contact with the printing plate during printing and which apply a thin film of dampening fluid to it, a vibrating distributor roller made of metal and which contacts with one or more of the dampening rollers in order to evenly distribute the fluid applied to the dampening rollers, and a ductor roller also preferably covered with molleton for conveying the fluid intermittently from the fountain roller to the distributor roller.

During the printing operation of an offset press the molleton cloth on the rollers of the dampening mechanism absorb a certain amount of ink which is picked up from the plate or form. This is particularly true with respect to the dampening rollers of said mechanism which directly contact the printing plate or form during printing.

This necessitates frequent removal of the dampening rollers so that they may be cleaned and reconditioned.

With the exception of the bottom or lower dampening roller, the rollers of the mechanism may be easily removed since they are exposed and therefore accessible for removal from their bearing sockets. However, this is not the case as regards the bottom dampening roller which is inaccessible due to its position and thus removal of the same has heretofore presented difficulties, with disturbance of the setting of the other rollers being unavoidable.

The principal object of the present invention, therefore, is the provision of means whereby the inaccessible lower dampening roller can be removed without difficulty and without disturb-

2

ing its setting or that of any other roller of the dampening mechanism.

Another object of the invention resides in the provision of supporting arms for the lower dampening roller having latch means which in operative position will support the bearings for the roller and lock the same in position.

Another and more specific object resides in the provision of supporting arms having latch means as described and which may be conveniently released by the operator to thereby release and permit removal of the bearings of the lower dampening roller from their sockets, the arms providing a track-way for the bearings to support the same upon release and which permits rolling movement of the released dampening roller to an accessible position.

Another object of the invention resides in the provision of supporting arms for the lower dampening roller equipped with a track-way and latch means as described, and wherein the parts are so constructed and arranged that the roller may be inserted in its sockets by supporting the bearings of the roller on the track-way and rolling the roller toward the socket end of the supporting arm. In this connection the latch means are urged outwardly upon insertion of the bearings in their respective sockets and the said latch means will automatically return to their operative position to lock the bearings in place since a spring urged push rod is associated with the latch means for yieldingly biasing the latch means in a locking position.

With these and various other objects in view, the invention may consist of certain novel features of construction and operation as will be more fully described and particularly pointed out in the specification, drawings and claims appended hereto.

In the drawings, which illustrate an embodiment of the invention, and wherein like reference characters are used to designate like parts:

Figure 1 is a sectional view taken substantially along line 1—1 of Figure 2 and showing dampening mechanism embodying the improvements of the invention;

Figure 2 is a horizontal sectional view taken substantially along line 2—2 of Figure 1 and showing the supporting arms for the lower dampening roller in plan elevation with parts in section; and

Figure 3 is a vertical sectional view along line 3—3 of Figure 1 showing constructional details of the socket portions of the supporting arms with latch means combined therewith in accordance with the invention.

Referring to the drawings, the numeral 10 indicates a plate carrying cylinder of the press having a printing plate or form 11 mounted thereon in the usual manner. In contact with the printing plate 11 are dampening rollers 12 and 13 preferably covered with molleton and which, in turn contact the metal distributing roller 14 mounted for rotation and which is generally reciprocated in an axial direction. The plate cylinder 10 is rotated by means forming part of the printing press and is suitably inked by inking rollers, such structure not being shown, however, since it forms no part of the present invention.

The means for supplying moisture to the distributing roller 14 includes a molleton covered ductor roller 15 suitably journaled and oscillated for intermittent contact with the distributing roller 14 and a metal fountain roller 16. The fountain roller 16 is suitably journaled by the water fountain 17 supported by frame structure of the press including side members 18 and 20. The journaling of the fountain roller is such as to cause the roller to dip into the water contained by the fountain 17. Moisture from the periphery of the fountain roller is thus picked up by the molleton covered ductor roller and transferred to the distributing roller. Said roller is provided at its respective ends with trunnion portions 21 by means of which the roller is journaled and supported for reciprocating movement as described. The dampening rollers 12 and 13 are likewise suitably journaled for rotation and supported for contact with the distributing roller. This structure will now be described.

Spaced supporting arms 22 are provided for the upper dampening roller 12, the arms being pivotally supported at their right hand end, Figure 1, from the frame of the press by means of the stud shafts 23 mounted in the side members 18 and 20 respectively. Each stud shaft has fixedly secured thereto or formed integral therewith a lever 24 located exteriorly of its respective side member and to the inside of each member the said stud shafts are suitably fixed to eccentrics 25. The right hand ends of the arms 22 are supported by their respective eccentric 25, which permits individual adjustment of the arms upon rotation of the stud shafts 23 to vary the position of the upper dampening roller 12 so as to secure proper contact of the dampening roller with the printing plate 11 carried by printing cylinder 10. Each supporting arm 22 at its left hand end is provided with an arcuate shaped socket formed by the portions 26 adapted to receive the ball bearing members 27, the said members 27 being suitably fixed to their respective trunnion portion 28 whereby the molleton covered dampening roller 12 is suitably supported and journaled by the spaced arms 22 with provision being made for conveniently removing the dampening roller from the arms for cleaning and replacement of said roller.

Whereas the upper dampening roller is supported for convenient access and ready removal, this is not the case with the lower dampening roller 13 which by reason of its location is relatively inaccessible. The inaccessible position of the lower dampening roller has heretofore presented difficulties and disturbance of the setting of the other rollers in removing and replacing the same has been generally unavoidable. The supporting arms for said lower roller have therefore been designed with the object in view of providing for easy removal of the lower roller by an operation that can be performed without any

difficulty on the part of the operator and without disturbing the setting of the other rollers of the dampening mechanism.

The supporting arms 30 for the lower dampening roller are shown in side elevation in Figure 1 and in plan elevation in Figure 2. The arms are identical in construction and are pivotally supported from the frame at their right hand end, Figure 1, by stud shafts 31 mounted for rotation in the side members 18 and 20, respectively. A lever 32 is suitably fixed to or formed integral with each stud shaft, being located exteriorly of its respective side member, and on the inside of each member the stud shafts are suitably fixed to eccentrics 33. The right hand ends of the arms 30 are supported by the eccentrics 33 which provides for adjustment of the arms individually upon rotation of the stud shafts 31 to vary the positioning of the lower dampening roller 13 whereby to secure proper contact with the printing plate 11 carried by printing cylinder 10. Said arms 30, as best shown in Figure 2, comprise a longitudinal member 34 which is extended at the rear end of the arm to form the hub portion 35 receiving the eccentric 33 as above described and said longitudinal member 34 is also extended at its forward end to provide a portion 36 having cored passages formed therein transversely of the portion identified respectively by numerals 37 and 38. Adjacent portions 35 and 36 the member 34 of each arm 30 is provided with transverse web sections 40 and 41, the said web sections being joined by a longitudinal part 42 extending parallel to 34 and providing the track-way 43. Part 42 and the track-way 43 continue forwardly beyond section 41 to provide the socket portion 44 of each arm 30. It will be observed that the socket portion 44 is semi-circular, the same terminating at 45, and which forms a substantially semi-circular enclosure adapted to receive the ball bearing members 46 suitably fixed to the trunnion portions 47 of the lower dampening roller 13 whereby the roller is supported by the arms 30 and suitably journaled for rotation.

The arms 30 are disposed as shown in Figure 2, with the track-ways 43 thereof positioned adjacent but in spaced relation to each other so that each track-way is in substantial alignment with a ball bearing member 46 which journals the lower dampening roller. Means are provided by the invention for locking each ball bearing within the socket portion 44 of its supporting arm, and when the locking means are released it will be understood that the bearings are free to drop from their socket portions and roll on the track-ways 43 in a rearward direction toward the right hand end of their supporting arms. This natural rearward rolling movement of the roller 13 when released automatically positions the same for convenient access and removal by the operator.

The socket portion of each arm includes an inside wall 48 which is integral therewith, the same forming with the socket portion an arcuate housing extending beyond section 41 in parallel relation with extension 36. The exterior wall of each socket portion at the top thereof is formed to provide spaced ears 50 which receive the tightening screw 51 for locking the pin 52 in adjusted rotated position, said pin having location in cored openings 49 and 37 provided therefor. Said pin supports the latch 53 which is located between the socket portion 44 of the arm and the extension 36 thereof. It will be seen from Figure 3 that pin 52 is suitably mounted by both the socket

portion and the extension and that the intermediate eccentric part 54 of the pin coacts with the latch 53 to pivotally support the same and additionally provide for adjustment of the latch whereby to adjust contact of the same with its respective bearing member 46. For this reason the latch 53 is approximately L-shape, having a locking end 55 which is disposed within slot 56 formed in the wall of each socket portion substantially diametrically opposite pin 52 so that the end 55 will be located within said notch when the latch depends vertically in locking position. The vertical locking position of the latch 53 is clearly shown in Figure 1, in which position the locking end 55 is disposed under and in contact with the bearing 46. Since the locking end is located below and in substantial vertical alignment with pin 52 it is clear that the latch is operative to lock the bearing 46 within its respective housing 44. For releasing the bearings for release of the lower dampening roller from the socket portions of the supporting arms 30 it is necessary to actuate latch 53 in a direction outwardly toward the left, the latch during such movement pivoting on eccentric portion 54 of the pin 52.

For actuating the latch 53 so that the same may be conveniently positioned by the operator in a locking or a released position, the invention provides a push rod indicated by numeral 58 and which extends in a parallel direction longitudinally of its respective supporting arm, having location between members 34 and 42 of its arm. Each push rod 58 at its left hand end is pivotally secured to the latch, the same being clearly disclosed in Figure 3, and numeral 59 indicating the screw for pivotally joining the said end of the push rod and the latch. The rod extends through section 41 which is provided with an opening 60 permitting passage of the rod. At its right hand end each push rod is provided with a handle 61, located approximately under web 40 and thus being conveniently positioned for actuation by the operator to effect swinging movement of the latch and to thereby locate the latch in its locking or released positions. For practical reasons it is preferred to yieldingly maintain each latch 53 in a locking position with respect to its associated socket portion and accordingly the push rods 58 each carry a coil spring 62, the spring being confined between section 41 and handle 61 so as to yieldingly bias its respective push rod in a direction toward the right and maintain the latch in a vertical locking position. Thus to move a latch to a released position it is necessary to actuate its respective push rod to compress the coil spring 62 carried by the rod.

An operative relation is maintained between the dampening rollers and the distributing roller, the former contacting the distributing roller and being held in contacting relation by linkage as clearly shown in Figure 1. The links 64 have pivotal connection with the arms 22 on the axis of the trunnion portions 28 and said links at 65 are suitably connected in a pivotal manner to the links 66. It will be observed that the connection between links 64 and 66 is effected on the axis of the distributing roller 14. Whereas links 64 are disposed on the respective sides of the upper roller 12 the links 66 are disposed on the respective sides of the lower dampening roller 13. For pivotally connecting the links 66 with their associated supporting arm 30, the forward extension 36 of each arm carries a pin 67, the same having location in bore 38 provided therefor. The pin is thus located at the center of

the housing portion 44 of its respective arm and the links 64 and 66 therefore permit bodily movement of the upper and lower dampening rollers in an arcuate path about the periphery of the distributing roller 14. Adjustment of the supporting arms 22 and 30 through actuation of their respective eccentric to properly position the dampening rollers with respect to the printing cylinder may therefore be effected in a manner which maintains the dampening rollers in proper contact with the distributing roller.

For removing the lower dampening roller 13 from the supporting arms 30 it is first necessary to remove the ductor roller 15. With the ductor roller out of the way a clear path is provided for the lower dampening roller and the same may have unobstructed movement in a direction rearwardly toward the operator. The latches 53 on the arms 30 are preferably released simultaneously by actuation of the push rods 58. Accordingly, the bearings 46 for the lower dampening roller are released and are free to drop out of their respective socket portions 44 which will automatically take place upon the latches assuming a released position. The bearings contact the track-ways 43 and roll on said track-ways in a direction toward the right where the operator can conveniently lift the roller from the supporting arms.

Replacing the lower dampening roller is accomplished substantially automatically with the minimum of effort on the part of the operator. The bearings are placed on the track-ways and the roller is caused to roll toward the socket portions of the arms. Insertion of the bearings within the socket portions will effect movement of the latches to a released position, whereupon the latches will automatically return to a locking position by reason of the tension applied by the coil springs 62. The latches are effective to lock the bearings within their respective socket portions and accordingly the lower dampening roller is properly positioned and journaled for rotation, although removal of the same presents no difficulties and can be accomplished without disturbing the setting of the other rollers.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. Dampening roller mechanism, in combination, an upper and lower dampening roller positioned in superposed relation for contact with a printing cylinder, a pair of spaced arms for supporting each roller, the arms for the lower dampening roller having socket portions formed integral therewith at one end, means on said arms extending substantially horizontally from the bottom of said socket portion and providing a track on which a dampening roller may be rolled into and out of engagement with the associated socket portion, and a self-locking latch pivotally supported by each said arm and associated with the socket portion thereof.

2. Dampening roller mechanism for printing presses, in combination, a plurality of dampening rollers for applying a fluid to a printing plate, supporting means for one of said dampening rollers including spaced arms having socket portions respectively at their roller supporting end, self-locking latch means pivoted to each arm in

associated relation with the socket portions thereof and having a locking and a released position, said latch means in locking position serving to lock the said dampening roller in journalling relation within the socket portions, a member pivotally connected to the depending end of said latch means and operable whereby to move said latch to its released position, and track means on said arms providing a substantially horizontal trackway extending from the bottom of its associated socket portion and permitting rolling of the dampening roller into and out of journalling relation with the respective socket portion.

3. Dampening roller mechanism, in combination, an upper and a lower dampening roller positioned in superposed relation for contact with a printing cylinder, supporting means for each roller including a pair of arms each pivotally supported at one end and journalling its roller at the other end, the pair of arms for the lower dampening roller including socket portions at its roller journalling end, latch means associated with each socket portion and having a locking and a released position therewith, and eccentric means adjustably fixed to each arm for pivotally supporting the latch means thereof, said eccentric means being adjustable whereby to adjust the locking position of the latch means.

4. Dampening roller mechanism, in combination, rollers for applying dampening fluid to a printing plate, supporting means for said rollers respectively having socket portions for journalling the rollers for rotation, the supporting means for one of said rollers including a pivoted latch member for locking the roller in its operative position, eccentric means for adjusting the locking position of said member, resilient means associated with said latch member and operative to move said member to its locking position upon insertion of the roller in said sockets, and means adapted to be actuated at a position remote from said sockets for disengaging the latch member to thereby effect release of the roller.

5. Dampening roller mechanism, in combination, a plurality of rollers for applying dampening fluid to a printing plate, supporting means for the rollers respectively including a pair of arms for each roller having socket portions for journalling the rollers for rotation, a pivoted latch associated with the socket portions for locking the roller in operative position, an eccentric stud for mounting said latch whereby the locking position of said latch may be adjusted, a track provided on each of said arms for guiding the roller into and out of said sockets, and spring means constantly urging said latch into a locking position, said latch being movable to a released position against the tension of said resilient means.

6. Dampening roller mechanism, in combination, an upper and a lower dampening roller positioned in superposed relation for contact with a

printing cylinder, supporting means for each roller including a pair of arms for each roller pivotally supported at one end and journalling its roller at the other end, the pair of arms for the lower dampening roller including socket portions at its roller journalling end, a pivoted latch member associated with each socket portion and having a locking and a released position with relation thereto, a manually operable plunger pivotally connected to the free end of said member for moving it to its released position, and resilient spring means concentrically mounted on said plunger to exert pressure between the head of said plunger and said socket portion for returning said plunger and thereby said member to its locking position after the roller is inserted.

7. Dampening roller mechanism in combination, an upper and a lower dampening roller positioned in superposed relation for contact with a printing cylinder, supporting means for each roller including a pair of arms each pivotally supported at one end and journalling its roller at the other end, the pair of arms for the lower dampening roller including socket portions at their roller journalling ends and track means for guiding said rollers into and out of said sockets, bearing members for the respective ends of said roller adapted to be located within the socket portions respectively to thereby journal the roller for rotation, self-locking latch means associated with each socket portion and having a locking and a released position with relation to a bearing member located within its socket, said latch means including a manually operable plunger pivotally connected to said latch for moving the latch to its released position, and a resilient coil spring concentrically mounted on said plunger for constantly urging said plunger and thereby said latch means to the locking position, said latch being movable to its released position against the resilient pressure of said spring upon the insertion of the roller in the socket whereupon the spring moves said latch to its locking position to thereafter retain said roller in the socket.
